US00D838296S

(12) **United States Design Patent** (10) **Patent No.:** **US D838,296 S**
(45) **Date of Patent:** **** Jan. 15, 2019**

(54) **SOWING DEVICE**

(71) Applicant: **MATERMACC S.P.A.**, San Vito Al Tagliamento (IT)

(72) Inventor: **Massimo Zubelli**, Gualtieri (IT)

(73) Assignee: **MATERMACC S.P.A.**, San Vito Al Tagliamento (PN) (IT)

(**) Term: **15 Years**

(21) Appl. No.: **35/501,733**

(22) Filed: **Apr. 20, 2016**

(80) **Hague Agreement Data**

Int. Filing Date: **Apr. 20, 2016**

Int. Reg. No.: **DM/090518**

Int. Reg. Date: **Apr. 20, 2016**

Int. Reg. Pub. Date: **Oct. 21, 2016**

(30) **Foreign Application Priority Data**

Nov. 6, 2015 (EM) 002849604-0001
